UNITED STATES PATENT OFFICE.

G. RALSTON AYRES, OF PHILADELPHIA, PENNSYLVANIA, ASSIGNOR TO HIMSELF, WILLIAM MONTGOMERY AYRES, AND LOUIS H. AYRES, ALL OF SAME PLACE.

DESIGN FOR A HORSE-BLANKET.

SPECIFICATION forming part of Design No. 18,485, dated July 31, 1888.

Application filed April 25, 1887. Serial No. 236,068. Term of patent 14 years.

To all whom it may concern:

Be it known that I, G. RALSTON AYRES, a citizen of the United States, and a resident of Philadelphia, Pennsylvania, have invented a new and original Design for a Horse-Blanket, of which the following is a specification.

My design is fully shown in the accompanying drawings, in which—

Figure 1 is a side view of a horse-blanket embodying the design; Fig. 2, an enlarged view showing the pattern more clearly, and Fig. 3 a similar view showing a modified form of the design.

The blanket has the curved back border, *a*, curved neck-border *b*, front and rear borders, *d* and *f*, and bottom border, *g*, and the body of the blanket has a plaid pattern formed by longitudinal and transverse stripes *m* and *n*. Both longitudinally and transversely the stripes *m* and *n* alternate, and each stripe is composed of alternating blocks of two different shades of color. Both the light and dark blocks of the stripes *m* are formed of narrow bars with intervening well-defined spaces, the dark blocks of said stripes *m* forming the light blocks of the stripes *n*, and the dark blocks of the latter stripes being composed of narrow bars crossing each other at right angles, so as to form diamond-shaped openings.

As shown in Fig. 2, the background of all 30 of the blocks is plain; but in Fig. 3 the background of the dark blocks of the stripes *m* and light blocks of the stripes *n* is shaded, this shading, however, being such as not to obscure the well-defined spaces between the 35 bars of which the blocks are composed.

I claim—

The within-described design for a pattern for horse-blankets, said design consisting of stripes *m* and *n*, alternating both longitudinally 40 and transversely, the stripes *m* being composed of alternating blocks, each formed of narrow bars with intervening well-defined spaces, and the stripes *n* being composed of blocks formed alternately of narrow bars with intervening 45 well-defined spaces and of narrow bars crossing each other at right angles and forming diamond-shaped openings, all substantially as shown and described.

In testimony whereof I have signed my name 50 to this specification in the presence of two subscribing witnesses.

G. RALSTON AYRES.
